YARN WINDING, DOUBLING, AND LIKE
MACHINE

Joseph Higginson, Stockport, England

Application July 15, 1933, Serial No. 680,621, and
in Great Britain April 26, 1932

8 Claims. (Cl. 242—38)

This invention relates to yarn winding, doubling and like machines, and particularly to high speed machines having automatic stop motion mechanism in which the cheese being wound is withdrawn from the drum by which it is rotated, and braked when an end breaks.

One of the objects of my present invention is to provide improved means for preventing yarn being drawn towards the cheese being wound by the guide bowl or bowls after knock-off has taken place. A further object of my invention is to provide means for ensuring that yarn is not drawn to any appreciable extent away from the detector mechanism due to the overrunning of the cheese after knock-off has occurred so that piecing up is facilitated. A still further object of my invention is to provide simple and efficient means for preventing damage to the yarn by the reciprocating guide when starting up the winding operation or "setting on".

My invention comprises the improved combinations and arrangements of parts hereinafter described.

Referring to the accompanying sheets of explanatory drawings:—

Figure 1 is a side elevation and Figure 2 a front elevation of part of a winding frame constructed in one convenient form in accordance with this invention.

Figure 3 is a side elevation showing a modification.

Figures 4 and 5 are enlarged detail views at right angles to one another of certain parts shown in Figures 1 and 2.

Figures 6 and 7 are enlarged detail views of the means for braking the upper guide bowls when an end breaks and knock-off occurs.

Figures 8 and 9 are respectively elevation and plan of the brake with its holder and clip as shown in Figures 6 and 7.

Figure 10 is a detail view of the braking means for the lower guide bowl shown in Figures 1, 2 and 3.

The same reference letters in the different views indicate the same or similar parts.

a indicates a cradle carrying the bobbin *b* being wound. Each cradle is pivotally carried at *c* by a stop lever *d* which when its particular bobbin *b* is in contact with the rotating drum *e* for winding purposes, is supported by the arm *f* upon the detector in the known manner. A detector wire is shown at *g*. The stop lever *d* is pivoted at *h* to a fixed bracket *i*. The arm *j* which is an extension of the cradle *a* below its pivot point is connected to a chain *k* which passes round two

pulleys *m* and is anchored by means of a spring *n* to a stud *o* forming the axle of one of the pulleys *m* and adjustable in a long slot in the bracket *p*.

There is a brake *q* pivoted at *r* and resting upon a cam *s* pivoted to the cradle at *t*, the said cam being supported by the adjustable stud *u*. When the detector arm *f* ceases to support the stop lever *d*, due to an end breaking, the stop lever falls and the bobbin *b* is lowered clear of the drum *e* and on to the brake *q* which is also moved forward by the pivotal movement of the cam member *s*.

Connected to the stop lever *d* by a link or wire *v* is an arm *w* pivoted at *w* to a fixed bracket *x*. The said arm is adapted to engage an adjustable stop *y* upon a lever *z* pivoted at *z* to the bracket *x*. The lever *z* carries a yarn deflector 3. A torsion spring 3^a acting on the lever *z* tends always to move the deflector 3 from the full to the dotted line position, the amount of such movement being limited by the deflector engaging a lug 10 on the bracket *x*. The yarn from the detector wire *g* passes around bowls or rollers 4, 5 and 6 and through a reciprocating guide 7.

When the stop lever *d* is unsupported by the detector arm *f*, the wire link *v* lowers the arm *w* and the deflector 3 rises to the dotted line position in Figure 1 and is held there by the lug 10. In this position the deflector moves the yarn clear of the path of the guide 7 so that it is not damaged by the latter. When the stop lever *d* is raised in the ordinary way to start winding, the first movement of *d* merely takes up the gap between the arm *w* and the stop *y* on the lever *z* without moving the deflector 3. It is only the last portion of the movement of *d* which causes the deflector to allow the yarn to come into the path of the guide 7, but the bobbin *b* is then being driven by the drum *e*.

A second link 11 connected to the cradle *a* is attached to a lever 12 pivoted upon the bracket *x*. The lever 12 carries an adjustable stop in the form of a stud 13 which is adapted to engage beneath an arm 14 pivoted at 15 in the bracket *x* and carrying at its outer end the bowl or roller 5. The arm 14 when unsupported by the lever 12 rests upon the bracket *x*, a lug 17 on the arm resting on the top of the bracket. When the stop lever *d* is unsupported by the detector arm *f*, the link wire 11 causes the lever 12 to raise the arm 14 and the bowl 5. The yarn path between the three bowls is thereby shortened, the shortening tending to compensate for the amount of yarn which may be wound upon the bobbin *b* after the deflector operates and before the bob- 110

bin comes to rest. By this means I ensure that piecing up is made in the length between the detector and the front bowl 4 instead of the break being carried forward on to the back bowl 6 and on to the bobbin. By providing for the lost motion between the lever 12 and the arm 14, I ensure that the latter is not lifted until the bobbin has completely cleared the drum *e* and that therefore the slackness of the yarn path does compensate for any over-run of the bobbin.

As shown in Figure 3, instead of raising the lower bowl 5, I lower the upper bowl 6 by a link and lever mechanism operated from the stop lever *d*. It will be seen that a link or rod 20 connected to the stop lever *d* is coupled to a lever 21 attached by a link 22 to an arm 23 carrying the rear bowl 6. The link 20 has an eye 20^a therein to clear a fixed rod 24. It will be noted that as the bowl 6 is lowered it is also drawn forward so that the yarn is moved clear of the path of the yarn guide. The bowl 6 therefore accomplishes the dual object of shortening the yarn path and preventing the yarn guide damaging the yarn when winding ceases.

Several threads, each passing through its own detector wire, may be doubled together and wound upon the bobbin or cheese *b*.

In the construction illustrated, each of the upper bowls 4 and 6 is adapted to have a brake 25 applied thereto when knock-off occurs. The brake material which may be leather is held in a socket or holder 26 secured to an extension of a spring clip 27, each of the latter embracing and gripping a spindle 28 having a crank arm 29 at its rear end. Through said crank arm passes a rod 30 connected at its lower end to an extension of the stop lever *d*. A spring 31 around said rod 30 rests at its lower end on a washer 32 on a shoulder on the rod 30 and at its upper end, the crank arm 29 rests thereon. With this construction, when knock-off occurs, the rod 30 is raised and tends to compress the spring 31 against the arm 29, resulting in the turning of the spindle 28 and the application of the brakes to the bowls 4 and 6. When the brakes are applied, the spindle 28 can turn within the spring clip, so holding the brakes on whilst allowing the rod 30 to have a considerable movement. When the rod 30 moves downwards, that is when the machine is set on, the brakes are released from the bowls 4 and 6 and the brake holders brought against the part 33 of the bowl bracket, which forms a stop to limit the downward movement of the brake holder. Further turning movement of the spindle 28 results in said spindle slipping in the spring grips 27. It follows therefore that the brake holders always rest in a definite position with relation to the bowls to be braked so that individual adjustment of the brake holders to compensate for differences in the brake pads is obviated. It follows also that all the brakes will be fully applied if the travel of the rod is sufficiently long to cause slipping between the clips or grips 27 and the spindle 28.

The connection between the end of the stop lever *d* and the rod 30 may be by pin and slot 34 so that when the stop lever (the movement of which is very rapid) strikes the pin on the rod 30, the latter will be forced upwards momentarily until the pin on 30 is at the top of the slot 34 during which the brakes will be fully applied. The rod 30 will then fall until the pin thereon is at the bottom of the slot, when the brakes will be released.

It will be understood that a brake may be applied to only one of the two bowls 4 and 6, preferably the back bowl 6.

In the case of the brake 36 for the lower bowl 5 (see Figure 10), this is carried in a holder 37 upon a plate 38 pivoted at 39 (by being secured to a pin in the turned over end of a plate 40) and having a weight 41 connected thereto by a spring 42. When the lower bowl 5 is thrown upwards by the arm 14 as previously described, when knock-off occurs, the weight 41 will by its inertia first fail to follow the movement of 14 and will then by the co-operation of the spring 42 cause the application of the brake 36 to the bowl 5. Several applications of the brake will occur before the weight 4 comes to rest.

What I claim is:

1. In yarn winding, doubling and like machines, in combination, a stop lever, a cradle pivoted upon said lever, a bobbin carried by said cradle, a driving drum rotating said bobbin, means moving said cradle to press the bobbin against the drum, a brake for the bobbin below said drum, a detector arm to support said stop lever during winding, a reciprocatory yarn guide for laying the yarn upon the bobbin, a bowl over which the yarn passes on its way to the said bobbin, a brake for said bowl, a spring clip carrying the brake, a spindle embraced and gripped by said clip, a connection between said spindle and said stop lever to apply the brake when the stop lever drops, a stop limiting the extent of movement of the brake away from the bowl, the turning movement of the spindle being of sufficient extent to ensure that the brake comes against the bowl and against the stop at each brake application and release.

2. In yarn winding, doubling and like machines, in combination, a stop lever, a cradle pivoted upon said lever, a bobbin carried by said cradle, a driving drum rotating said bobbin, means moving said cradle to press the bobbin against the drum, a brake for the bobbin below said drum, a detector arm supporting said stop lever during winding, a reciprocatory yarn guide for laying the yarn upon the bobbin, two upper and one lower bowl around which the yarn passes on its way to the said bobbin, a brake for each of said upper bowls, a spring clip carrying each brake, a spindle embraced and gripped by said spring clip, a connection between said spindle and said stop lever to apply the brake when the stop lever drops, a stop limiting the extent of movement of each brake away from its bowl, the turning movement of the spindle being more than necessary to bring the brakes against their drums and stops at each brake application and release.

3. In the combination claimed in claim 1, a connection between the brake carrying spindle and the stop lever comprising a crank arm upon the spindle, a rod extending freely through said crank arm, a spring supported by the rod and abutting against the crank arm, the said rod being connected to the stop lever.

4. In yarn winding, doubling and like machines, in combination, a stop lever, a cradle pivoted upon said lever, a bobbin carried by said cradle, a driving drum rotating said bobbin, means moving said cradle to press the bobbin against the drum, a detector arm supporting said stop lever during winding, a bowl over which the yarn passes on its way to the said bobbin, an arm carrying said bowl, means connecting said arm to said stop lever to shorten the yarn path to the bobbin when the stop lever falls, a brake for the bobbin below the

drum, and a reciprocatory yarn guide for laying the yarn upon the bobbin.

5. In yarn winding, doubling and like machines as claimed in claim 4, an inertia brake for said bowl which applies itself automatically when the bowl is moved by the stop lever to stop the machine and shorten the yarn path to the bobbin.

6. In yarn winding, doubling and like machines, in combination, a stop lever, a cradle pivoted upon said lever, a bobbin carried by said cradle, a driving drum rotating said bobbin, means moving said cradle to press the bobbin against the drum, a brake for the bobbin below said drum, a detector arm to support said stop lever during winding, a reciprocatory yarn guide for laying the yarn upon the bobbin, a bowl over which the yarn passes on its way to the said bobbin, an arm adjacent to the

yarn near the reciprocatory guide, a connection between said arm and stop lever which causes the arm to move the yarn clear of said guide when the stop lever falls to stop winding.

7. In yarn winding, doubling and like machines as claimed in claim 2, an arm carrying the lower bowl, a connection between said arm and the stop lever which raises the bowl when the stop lever falls to stop winding, an inertia brake for said bowl which applies itself automatically when the bowl is raised.

8. In yarn winding, doubling and like machines, as claimed in claim 1, a pin and elongated slot connection for the rod operating the brake spindle so that the brake application is momentary only.
